DESIGN FOR A CAMERA

Philmore F. Sperry, Philip F. Briskin, and Jack Briskin, Chicago, Ill., assignors to Revere Camera Company, Chicago, Ill., a corporation of Delaware

Application September 6, 1941, Serial No. 103,196

Term of patent 14 years

To all whom it may concern:

Be it known that we, Philmore F. Sperry, Philip F. Briskin, and Jack Briskin, citizens of the United States, residing at Chicago, in the county of Cook and State of Illinois, have invented a new, original, and ornamental Design for Cameras, of which the following is a specification, reference being had to the accompanying drawings, forming part thereof.

Fig. 1 is an elevation of one side of a camera embodying our new design;

Fig. 2 is a front end view of the camera;
Fig. 3 is a bottom face view of the camera;
Fig. 4 is a rear end view of the camera;
Fig. 5 is an elevation of the opposite side of the camera from that shown in Fig. 1; and
Fig. 6 is a top plan view of the camera.

We claim:

The ornamental design for a camera, as shown.
PHILMORE F. SPERRY.
